THOMAS E. CLARK, OF DETROIT, MICHIGAN.

BRAKE-RELEASING MECHANISM.

1,262,637.

Specification of Letters Patent. Patented Apr. 16, 1918.

Application filed April 28, 1913. Serial No. 763,965.

To all whom it may concern:

Be it known that I, THOMAS E. CLARK, a citizen of the United States, and a resident of Detroit, in the county of Wayne and State of Michigan, have invented a new and Improved Brake-Releasing Mechanism, of which the following is a specification.

This invention relates to automatic train control apparatus designed for use in connection with block signal systems for the control of railway trains, and especially to that type shown in my prior application Serial Number 679,803, filed Feb. 26, 1912, and consists in the mechanism shown in said application whereby the train crew can cause the release of the train brakes after they have been set because of conditions against which this train control apparatus is designed to guard the train.

20 This invention consists particularly in an electric circuit and manually operated switches mounted therein, whereby the brakes are caused to release notwithstanding the danger conditions which may exist in 25 the path of the train, so that the train can proceed.

It further consists of automatic mechanism for limiting the speed of the train while the brakes are prevented from operating by said brake-releasing switches and the circuits therefor.

In the accompanying drawing, Figure 1 is a diagrammatic view of this invention. Fig. 2 is a diagrammatic view of a modification embodying a plurality of control switches in series.

Similar reference characters refer to like parts in the several views and are generally the same as those which refer to like parts 40 in the drawings of said former application Number 679,803.

The track equipment of each block A, B and C will be the same as described in said prior application, and consists of the feed 45 wires 6 and 7, the track-circuit wires 8 and 9 connecting to the ends of the rails of the next adjacent track and which connect to the track relay or electro-magnet 10, the primary coil of the transformer 14, the circuit 50 of which includes a reactance regulator 15 and the armature 16 of the electro-magnet 10, the lines 17 and 18 connecting to the armature 16 and the reactance regulator, and the switch 19 connecting this circuit to the 55 lines 6 and 7.

This drawing further shows the secondary

coil of the transformer 14, the rotary interrupter 29—30 (which is fully explained in my application Serial Number 702,013, filed June 6, 1912), the electrodes 31 so positioned 60 as to leave spark gaps 20 between their inner ends and the rotary interrupter, the condensers 23, the copper inductance or linking coil 24, the adjustable line 21 connecting thereto, the adjustable line 25 leading to the main limb 27 of the wayside circuit and the line 26 leading to the pick-up limb 28 of this circuit, which limbs are out of alignment but parallel with each other and with the track rails α . In this case as in the original application, the track is divided into blocks insulated from each other, and while the short limb 28 of each block terminates at the insulation at the forward end of the block, the main limb 27 extends beyond the insulation 70 at the other end of the block into the next adjacent block.

The receiving circuits, and the local operating circuit mounted on the locomotive or tender, are shown in substantially the same 80 manner as in the former application, parts being omitted wherever possible. The main receiving circuit when in operation consists of the same main receiving members 53 connecting to the line 54 which leads to one of 85 the contacts controlled by the main relay (here shown) as made up of two independent parts 57 and 57^a, movable contact 97 of the relay, the line 59 connecting to the thermo-electric relay 60 (which is described in detail 90 in my former application Serial Number 680,970, dated March 1, 1912), the line 59^a the variable inductance 61 and the ground 62.

The auxiliary or pick-up branch circuit, when in operation, comprises the receiving 95 members 63, the line 64 including the variable inductance 64^a the relay armature 97 (when in the position shown in Fig. 1), and line 59 to the thermo-electric relay 60, the line 59^a, the inductance 61 and the ground 100 62. This pick-up circuit is closed when the relay 57^a is deenergized, and being thus closed is the first to receive current influence from the wayside circuit.

The local circuit comprises the thermo-electric relay, the lines 67 and 67^a, the windings of the magnets 57 and 57^a and the bus-bars 68 and 69, which connect to the current source 70 by lines 71 and 71^a, and the switch 72. The thermo-electric relay has the 105 case 60, the wire filament 78, the tensioning spring 75, the flexible fiber 81 and the switch 110

86, as described in my prior application No. 680,970, and so long as proper current passes over the filament 78 between the lines 59 and 59^a, permits an operative current from the 5 source 70 to flow over the lines 67 and 67^a.

The main function of the relay 57 is to keep closed the circuit to the solenoid 99 so long as current is impressed upon the receiving circuits from the wayside wires 27 10 and 28, and this will occur so long as a connection exists in the thermo-electric relay between the wires 67 and 67^a. The path of the current will be from the bus-bar 68 over the line 101 to the armature 103, over 15 the line 105 and the line 106 to the binding post 107 of the solenoid coil 99, thence from binding post 108 over the line 110 to the bus-bar 69. This causes the core 111 of the solenoid to actuate the stem 113 to close the 20 valve 112 in the train air-pipe 114. The valve will automatically open when the solenoid is deenergized, thus causing the brakes to operate and stop the train.

The passage of current through the 25 solenoid depends on the passage of current to the wayside circuit. If this is interrupted, the train on that particular block will be stopped. The relay 10 is energized by the current in the rails of the next block ahead 30 in the direction the trains run. If a car 138 short circuits the rails of block C, the relay 10 of block B is deprived of sufficient current and current ceases to flow in the wayside circuit of that block, and train 128 35 is held stationary by its brakes.

Should the engine-man desire to release the brakes of his train and go ahead slowly under check, he may do so by closing the self-opening switch 139, which may be of 40 any desired construction, which will close the circuit across the terminals of the line 127 connecting to the bus-bar 69, the line 160, contacts 161 and 162, line 163, line 143, the winding of the magnet 142, the line 141, 45 the contacts 164 and 166, the line 135, the armature 103 and the wire 101 to the bus-bar 68. The magnet 142 causes its armature 144 to press the contacts 148 and 149 toward each other, closing the circuit from the bus-bar 68 over the line 150, the contacts 149 50 and 148, the lines 151 and 106 to the binding post 107, the winding of the solenoid 99, the binding post 108 and the line 110 to the bus-bar 69. The energized solenoid will 55 close the valve 112 and hold it in that position so long as it is energized. The electro-magnet 142 is preferably in the form of a slow acting "stick relay" so that it will keep the contacts 148 and 149 in engagement 60 while the armature 103 is changing from contact with the end of 135 to contact with the end of 105.

When the magnet 142 is energized it will 65 press the contacts 145 and 146 together, causing current to pass from the bus-bar 68

over the line 101, armature 103, line 135, contacts 166 and 164, line 141, the winding of the magnet 142, line 143, line 140, contacts 145 and 146, line 127 to the bus-bar 69. This circuit will now remain closed so long as the 70 armature 103 is in circuit with the line 135, and therefore, the magnet 142 will remain energized even if the switch 139 is opened. This permits the engineer to release his switch immediately after closing it, and 75 relieves him of the necessity of holding it closed. As soon as current passes from the wayside circuit over the line 54 or 64, the magnet 57 will be energized and the circuit between the armature 103 and line 135 will 80 be broken, and the contacts 145 and 146 will separate, but the circuit to the solenoid 99 over the line 105 will be closed simultaneously with the opening of the circuit to this solenoid over the line 135, so that there 85 will be no opening of the valve 112 because of such change.

To prevent the blocked train from proceeding at too high speed, a small generator 90 170 may be mounted on the locomotive or tender, which generator may be driven from an axle 171 in any desired manner, as by a friction wheel 172 secured to the axle 171 and engaging the wheel 173 on the generator shaft 174. A slow acting electro-magnet 175 is provided with an armature 176 adapted to separate the contacts 161 and 162 and the contacts 164 and 166, whenever the magnet is sufficiently energized, which occurs whenever the generator shaft 174 has attained the predetermined speed which will cause a sufficient current to pass over the lines 177 and 178. The slow-acting magnet 175 will keep the circuits to the solenoid 99 open for a time after the speed of the train 95 has fallen below the predetermined point. The separation of the contacts 164 and 166 will open the circuit to the magnet 142, releasing the armature 144 and permitting the contacts 145 and 146 to separate, and thus open the circuit to the solenoid 99 and permit the opening of the train pipe 114. This will result in the train being stopped 100 whenever it exceeds a predetermined speed when running along in a block whose wayside circuit is not receiving a proper current. This also opens the circuit to the switch 139 so that the brakes will be set 105 even if the engineer keeps this switch closed.

In order to place a check on the engineer, the circuit of the lines 160 and 127 may be extended so that a second switch 139^a may be placed in series with the switch 139, as shown in Fig. 2. This second switch may be placed where it can be operated by the 110 fireman or be placed in one of the coaches where it can be operated by the conductor. In such case the engineer and conductor must close their switches simultaneously before the train can proceed in a block after 115 125 130

the train has been stopped because of lack of proper current in the receiving circuits.

It will be understood that when a train is stopped because of the presence of another train in the block ahead, the stopped train will be released as soon as the other train passes from the block ahead into the second block ahead, for at such passing the lines 8 and 9 of the block ahead again carry sufficient current to the relay 10, causing current to pass to the wayside circuit and to the receiving circuit of the stopped train.

I claim.

1. In railway-train control apparatus adapted for use in connection with wayside circuits connected to sources of high potential oscillating current, the combination of a vehicle on a track, a receiving conductor mounted on the vehicle, a main relay, a thermo-electric relay connected to said conductor to control the main relay, a ground wire connected to said thermo-electric relay, a current source mounted on the vehicle, a safety device for the vehicle, electrically operated means to hold the safety device inoperative when current is present in the wayside circuit, an electric circuit between the current source, the controlling means for the safety device and the main relay which may be opened by the main relay to permit the actuation of the safety device when current is absent from the wayside circuit, manually operable controlling means whereby the safety device may be caused to be inoperative during the time current is absent from the wayside circuit, and means for again causing the safety device to become operative whenever the speed of the vehicle exceeds a predetermined amount during the time no proper current is received by the receiving conductor, said last mentioned means being immediately rendered inoperative for the purpose set forth when proper current is received by the receiving conductor.

2. In railway-train control apparatus adapted for use in connection with wayside circuits connected to sources of high potential oscillating current, the combination of a vehicle on a track, a receiving conductor mounted on the vehicle, a main relay, a thermo-electric relay connected to said conductor to control the main relay, a ground wire connected to said thermo-electric relay, a current source mounted on the vehicle, a safety device for the vehicle, electrically operated means to hold the safety device inoperative when current is present in the wayside circuit, an electric circuit between the current source, the controlling means for the safety device and the main relay which may be opened by the main relay to permit the actuation of the safety device when current is absent from the wayside circuit, manually operable controlling means whereby the

safety device may be caused to be inoperative during the time current is absent from the wayside circuit, and an electrical generator connected to the vehicle to be driven according to the speed thereof, and an electrically operated device connected to said generator and energized when the vehicle exceeds a predetermined speed to break the circuit between the circuit closer and said safety device.

3. In railway-train control apparatus adapted for use in connection with wayside circuits connected to sources of high potential oscillating current, the combination of a vehicle on a track, a receiving conductor mounted on the vehicle, a main relay, a thermo-electric relay connected to said conductor to control the main relay, a ground wire connected to said thermo-electric relay, a current source mounted on the vehicle, a safety device for the vehicle, electrically operated means to hold the safety device inoperative when current is present in the wayside circuit, an electric circuit between the current source, the controlling means for the safety device and the main relay which may be opened by the main relay to permit the actuation of the safety device when current is absent from the wayside circuit, manually operable controlling means whereby the safety device may be caused to be inoperative during the time current is absent from the wayside circuit, and an electrical generator connected to the vehicle to be driven according to the speed thereof, and an electrically operated device connected to said generator and energized when the vehicle exceeds a predetermined speed to break the circuit between the circuit closer and said safety device, said generator and electrically operated device becoming inoperative immediately for the purpose set forth when proper current is received by the receiving conductor.

4. In a railway-train control apparatus adapted for use in connection with wayside circuits connected to sources of high potential oscillating current, the combination of a vehicle on a track, a receiving conductor mounted on the vehicle and spaced apart from the wayside circuit and having an element adjacent to the wayside circuit, a thermo-electric relay connected to said receiving conductor to control the main relay, a ground wire connected to the relay, a current source mounted on the vehicle, a safety device for the vehicle, means normally tending to force said safety device into operative position, an electro-magnet and a circuit therefor whereby the safety device is held in inoperative position against the force of the previously mentioned means whenever current is present in the receiving conductor, which last mentioned circuit is opened by the main relay whenever current is absent

- from the receiving conductor whereby the safety device is allowed to become operative, manually operable controlling means whereby the safety device may be caused to be 5 inoperative during the time current is absent from the receiving conductor, and means for again causing the safety device to become operative whenever the speed of the vehicle exceeds a predetermined amount during the time current is absent from the receiving conductor, said last-mentioned means being immediately rendered inoperative for the purpose set forth through the instrumentality of the wayside circuit whenever current is present therein. 15
5. In a railway-train control apparatus adapted for use in connection with wayside circuits connected to sources of high potential oscillating current, the combination of 20 a vehicle on a track, a receiving conductor mounted on the vehicle, a thermo-electric relay connected to said conductor to control the main relay, a ground wire connected to said relay, a current source mounted on the 25 vehicle, a main relay, a safety device for the vehicle, electrically operated means to hold the safety device inoperative when current is present in the wayside circuit, an electric circuit between the current source, 30 the electrically operated means and the relays, which circuit may be opened by the relay and thus permit the actuation of the safety device when current is absent from the wayside circuit, manually operable controlling means and an additional circuit 35 whereby the safety device may be caused to be inoperative during the time current is absent from the wayside circuit, and means for again causing the safety device to be 40 come operative whenever the speed of the vehicle exceeds a predetermined amount during the time current is absent from the wayside circuit, said last-mentioned means being immediately rendered inoperative for the purpose set forth through the instrumentality of the wayside circuit whenever current is present therein. 45
6. In a railway-train control apparatus adapted for use in connection with wayside 50 circuits connected to sources of high potential oscillating current, the combination of a vehicle on a track, a receiving conductor mounted on the vehicle and spaced apart from the wayside circuit, an electrically 55 operated safety device mounted on the vehicle, a main relay, a current source mounted on the vehicle, a thermo-electric relay in the receiving conductor to control the main relay, circuits connecting the relays, 60 the current source and the safety device whereby the safety device is held inoperative during the time current is present in the wayside circuit and said circuit is opened by the main relay so that the safety device 65 is normally caused to become operative whenever current is absent from the wayside conductor, manually controlled means and separate circuits whereby the safety device may be caused to be inoperative during the time current is absent from the wayside circuit, and means for again causing the safety device to become operative whenever the speed of the vehicle exceeds a predetermined amount during the time current is absent from the wayside circuit, said last-mentioned means being immediately rendered inoperative for the purpose set forth through the instrumentality of the wayside circuit whenever current is present therein. 70
7. In a railway-train control apparatus 75 adapted for use in connection with wayside circuits connected to sources of high potential oscillating current, the combination of a vehicle on a track, a receiving conductor on the vehicle adjacent to but separated from the wayside circuit, a current source on the vehicle, a thermo-electric relay in the receiving conductor, a main relay controlled by the thermo-electric relay, circuits connecting the relays, the current source on the vehicle and the safety device, said receiving conductor being connected to said thermo-electric relay to cause the same to connect the main relay to the current source, and thereby cause the connection of the current 80 source to the safety device so that the safety device will be held normally inoperative during the time current is present in the receiving circuit, a manually closable circuit between the current source and the safety 85 device to render the safety device inoperative during the time current is absent from the receiving circuit, and means for preventing the safety device from operating, means for causing said preventing means to be 90 held normally inoperative whenever the speed of the vehicle exceeds a predetermined amount during the time current is absent from the receiving conductor, said last-mentioned means being immediately rendered inoperative for the purpose set forth through the instrumentality of the wayside circuit whenever current is present therein. 95
8. In train control apparatus adapted for use with a track provided with a wayside 100 circuit, the combination of a vehicle, a current source and a safety device on the vehicle and a circuit connecting them, a main relay to close the circuit, a circuit between the current source and the main relay, a secondary circuit mounted on the vehicle and having a portion adjacent the wayside circuit, a thermo-electric relay, the secondary circuit connected to the thermo-electric relay to cause the same to close the circuit between the main relay and the current source to cause the main relay to close the circuit between the current source and the safety device whereby the safety device is normally held in inoperative position when current is 105 110 115 120 125 130

present in the wayside circuit, and a manually closable auxiliary circuit between the current source and the safety device whereby the safety device may be prevented from 5 operating during the time current is absent in the wayside circuit, and means for again causing the preventing means to become inoperative whenever the speed of the vehicle exceeds a predetermined amount during the 10 time current is absent from the wayside circuit, said last-mentioned means being immediately rendered inoperative for the purpose set forth through the instrumentality of the wayside circuit whenever current is present 15 therein.

9. In a train control apparatus, the combination of the train valve of a brake mechanism for a railway vehicle, an electrical device to close the valve, a current source, a 20 main relay, a circuit between the main relay, said electrical device and the current source, a second relay, a receiving conductor connected thereto, a circuit between the current source and the two relays which controls the 25 energization of the main relay and is opened whenever the second relay is deenergized, a manually operable circuit closer, and a circuit between said circuit closer, the current source, the main relay and the train valve 30 controlling device which circuit is open when the main relay is energized and may be closed by the manually operable circuit

closer when the main relay is deenergized, in order that the train valve may be closed.

10. In a train control apparatus, the combination of the train valve of a brake mechanism for a railway vehicle, an electrical device to control the valve, a current source, a main relay, a circuit between the main relay, said electrical device and the current source, a second relay, a receiving conductor connected thereto, a circuit between the current source and the two relays which controls the energization of the main relay and is opened whenever the second relay is deenergized, 40 a manually operable circuit closer, a circuit between said circuit closer, the current source, the main relay and the train valve controlling device which circuit is open when the main relay is energized and 45 may be closed by the manually operable circuit closer when the main relay is deenergized, in order that the train valve may be closed, and means to open said last named circuit when the vehicle exceeds a predetermined speed.

In testimony whereof I have signed this specification in the presence of two subscribing witnesses.
